UNITED STATES PATENT OFFICE.

JUSEF KRAUZ, OF FRANKLIN, NEW HAMPSHIRE.

CARRIER.

1,308,759.

Specification of Letters Patent.

Patented July 8, 1919.

Application filed November 12, 1918. Serial No. 262,136.

To all whom it may concern:

Be it known that I, JUSEF KRAUZ, a subject of the Emperor of Austria, residing at Franklin, county of Merrimack and State 5 of New Hampshire, have invented certain new and useful Improvements in Carriers, of which the following is a specification.

This invention relates to improvements in carriers, particularly adapted to convey the 10 wounded from a battlefield or from place to place, as may be desired.

The principal object of the invention is to provide an exceedingly flexible, strong, and comfortable carrier of the class described, 15 which is capable of being compactly folded into a small parcel when not required for use.

A further object is to provide a carrier in which a wounded or sick person may be conveniently transported upon the back of another without discomfort to either, and without impeding the natural actions of the carrier in any way.

These and other like objects are obtained 25 by the novel construction and combination of parts hereinafter described, and shown in the accompanying drawings, forming a material part of this disclosure, and in which:—

30 Figure 1 is a side elevational view indicating the application of the invention.

Fig. 2 is a side elevational view showing the carrier extended for use, and

35 Fig. 3 is a front elevational view of the same.

Referring to the drawings, the numeral 10 designates the carrier and 11 the party carried, the latter resting in a concave, basket-like receptacle 14 preferably formed of canvas or like strong textile fabric. To the upper edge of the receptacle 14 at the front and midway of the same are secured the straps 15 and 16 respectively, the front strap 15 being provided with a buckle 17 the 40 tongue of which engages within perforations 18 formed in the opposite strap, therefore permitting the straps to be secured over the breast of the carrier 10. The central strap 16 is unbroken in its length and like the 45 straps 15 is securely attached at its ends to

the sides of the basket 14. A pair of rear straps 20 are similarly engaged with the margins of the basket and are secured by stitchings or other means to the uppermost portion of the center strap 16 and at 22 adjacent to the ends of the front straps 15 the straps thus passing over the shoulders of the carrier in an obvious manner. 55

In operation the party to be carried is seated within the basket 14, after which the attendant places his arms, through the openings or spaces between the front and center straps 15 and 16 and engages the buckle 17 with the end of the strap in front of his breast, thereby supporting the carrier in 60 such manner as to be easily carried and without discomfort to either person. In view of the extreme flexibility of the structure no shock or jar of any consequence is transmitted to the carrier, and obviously there 65 are no parts to interfere with either the upper or lower limbs of either party. 70

From the foregoing it will be seen that the device is capable of being very compactly folded, all of its parts being extremely pliable and in which the wounded may be transported from place to place in any desired manner. 75

Having thus described my invention what I claim as new and desire to secure by Letters Patent, is:—

A carrier for use by ambulance attendants for carrying wounded soldiers, comprising a bowl-shaped seat of textile material, a pair of front straps attached with their lower 85 ends in spaced relation to the front part of said seat, a buckle connection for the upper ends of said straps in front of the attendant's chest, a strap attached to said seat at oppositely disposed points behind said 90 front straps, adapted to be placed upon the neck of the attendant, and a pair of shoulder straps engaged in close proximity at the rear part of the seat and connected with their other ends to the front straps in proximity to the ends thereof. 95

In testimony whereof I have affixed my signature.

JUSEF KRAUZ.

Copies of this patent may be obtained for five cents each, by addressing the "Commissioner of Patents, Washington, D. C."
